AUDIBLE AND VISUAL ELECTRICAL SIGNALING DEVICE

Eugene Weissman, Baltimore, Md.

Application May 29, 1945, Serial No. 596,471

10 Claims. (Cl. 177—324)

1

This invention relates to a signaling device. More specifically, the invention relates to a combined audible and visible signaling device and is characterized generally in the provision of a transformer having associated therewith sound and light producing means in circuit with the transformer and operative upon closing a switch as by means of a push button.

The improved device is specially adapted for use in place of the usual door bell and which, while functioning similarly to the usual door bells in providing an audible signal, also functions in the provision of a light, thereby providing a desirable signal for one who is wholly or partially deaf.

A primary object of the invention is the provision of a signaling device including a novel form of transformer having operatively associated therewith audible and visible signaling means.

A further object of the invention is the provision of a signaling device including a transformer having a primary coil and axially aligned spaced secondary coils, the secondary coils being in a circuit controlled by a push button switch, and a vibratory sound producing member interposed between the secondary coils and cooperating with opposed contacts in the circuit for alternate energization of the coils with a resultant vibration of the vibratory member.

A still further object of the invention is the provision of a signaling device of the above noted character wherein the sound volume is regulatable for a constant amplitude of vibration of the vibratory member.

A still further object of the invention is the provision of a signaling device of the above noted character which is relatively simple in construction, compact, neat in appearance, efficient in operation, and which is capable of being installed with a minimum of effort and skill.

With the foregoing and other objects in view, the invention consists in certain novel features of construction and arrangement of parts which will be hereinafter more fully described in connection with the accompanying drawings, wherein—

Figure 1 is a vertical sectional view in the plane of line 1—1, Fig. 2.

Fig. 2 is a vertical sectional view in the plane of line 2—2, Fig. 1.

Fig. 3 is a horizontal sectional view in the plane of line 3—3, Fig. 1, with certain parts omitted for clarity of disclosure.

Fig. 4 is a wiring diagram.

Referring now in detail to the drawings by use

2

of reference characters, 10 designates a casing or housing for the various cooperating elements entering into the improved signaling device. The casing preferably includes a base 11 in the form of a rectangular panel adapted for suitable support or connection to a wall, and a cover 12.

The cover 12 is constructed of a transparent material which may be glass or a plastic, and, in fact, the entire casing is preferably constructed of a plastic material, and the edge of the cover 12 is preferably undercut as at 13 for snugly receiving the margin of the base.

As will hereinafter appear, the mechanism within the casing is wholly supported by the base 11, and after assembly thereof, the cover 12 may be secured to the base in any desired or appropriate manner.

The cover 12 is provided with a socket member 14 for suitable connection to a house current, and such socket member may have binding posts 15 for connection of the terminals of a primary coil 16 on a core member 17 which may be suitably supported from the base 11, as by brackets 18. Also supported by the core member 17 is a pair of axially aligned secondary coils 19. The core member as shown in Fig. 1 is of generally U-form having inward extensions parallel with the base and upon which the secondary coils are wound, such extensions preferably terminating in opposed stops or poles 20, for a purpose later to appear.

Vertically disposed between the coils 19 and stops 20 is a yieldable vibratory strip member 21 whose lower end is rigidly supported as by means of brackets 22 projecting forwardly from the base 11 and which is provided with malleable iron armatures 21'. The upper end of member 21 is provided with a head 23 which is triangular in end view and which is disposed between opposed flanges 24 of resonance members. The resonance members are generally in the form of the well known tuning forks, and each includes opposed vertical tines 25, 26 connected through an arcuate bight portion 27.

The upper ends of the outer tines 25 are free while the corresponding ends of the inner tines 26 merge into horizontal plate portions 28 whose free and adjacent edges terminate in the flanges 24 above referred to.

As indicated in Fig. 1, the flanges 24 are angularly disposed and are substantially parallel with the adjacent faces of the head 23 for alternate impact by the head upon vibration of the member 21. The member 21 has a constant ampli-

tude of vibration as governed by the fixed stops 20 and armatures 21' and the extent of lateral vibration of the resonance members will be in accordance with the normal spacing of the flanges 24 from the adjacent faces of the head 23.

Means are provided for ready adjustment of this spacing for a corresponding change in the volume of sound produced by the resonance members. Such means preferably embodies a threaded stud 29 rigid with and projecting downwardly from each bight portion 27 and which projects loosely through an aperture in a bracket 30 projecting forwardly from the base 11. A coil spring 31 is disposed between the bight portion 27 and bracket 30 in surrounding relation to the stud 29 and a nut 32 is engaged with the stud 29 beneath the bracket 30.

Thus it will be seen that upon turning up the nuts 32 the resonance members with flanges 24 will be lowered with a corresponding decrease of spacing between the flanges and the head 23 and with a corresponding increase in the vibration amplitude of the resonance members.

On the other hand, upon turning the nuts toward the free ends of the studs, the springs 31 will urge the resonance members, together with flanges 24, upwardly with a corresponding increase of spacing between the flanges and head 23 whereby the vibratory amplitude of the resonance members will be diminished.

The opposed secondary coils 19 are alternately energized for imparting vibration to member 21 and such alternate energization is controlled by a pair of yieldable contacts 33 and 34 which project from brackets 35 rigid with the base 11 and which brackets are provided with circuit wire binding screws 36.

A pair of lamps 37 is supported in suitable brackets 38 on the base 11 and such brackets are preferably provided with circuit wire clamping screws 39.

The device is adapted for connection with wires leading from a suitable switch 40 (Fig. 4) controlled by a push button 41, and such wires may enter apertures 42 in the base 11, adjacent which apertures are circuit wire clamping screws 43.

As is diagrammatically indicated in Fig. 4, the secondary coils 19 are in the circuit with the lamps 37 through wires 44 and 45, and wires 46 and 47 connect the binding screws 43 with contacts 33 and 34, respectively. The coils 19 are connected with opposed contacts through wires 48 and 49 and the coils are jointly connected to member 21 through the wire 50.

As before stated, the cover 12 is transparent and preferably constructed of glass which is of such thickness as to have a vibration frequency equal to that of the resonance members whereby the casing will in effect act as a second resonance member in providing the sound signal.

It is to be noted that while the yieldable vibratory member 21 in its inoperative vertical position engages contact 33, the vibratory member will have equal amplitudes on either side of its vertical rest position, since the contacts 33 and 34 are yieldable even though the opposing coil 19 is energized upon contact 33 engaging the vibratory member before such member completes its amplitude of vibration.

In operation, the improved signaling device is suitably connected with the current through the socket member 14 and the primary coil 16 through the core 17 induces a low voltage current in the secondary coils 19 which through the circuit connections illustrated in Fig. 4 are alternately

energized with a resultant vibration of the member 21 upon pressing button 41.

The member 21 will have a constant amplitude of vibration as governed by the stops 20, and the head 23 will impart vibration to the resonance members of an amplitude dependent upon the spacing between the head and the flanges 24 which spacing is readily adjustable to provide any volume of sound desired.

10 The lamps 37 will also be lighted upon closing the switch 40 through the push button 41 which, due to the rapid rate of vibration of member 21, will result in a practically continuous lighting of the lamps.

15 Thus it will be seen that the improved signaling device will provide both an audible and a visible signal thereby suiting its use to persons whether blind or deaf.

It will further be seen that the cooperating 20 elements are all supported by the base of a neat casing having a transparent cover which may be readily removed for inspection of the elements or for repair or replacement thereof, and which cover also functions in harmony with the resonance member in providing an audible signal.

25 Furthermore, the device lends itself to ready assembly and connection with a house current and is well adapted for installation at any time and at any desired location in a building.

30 While I have disclosed my invention in the form of a single specific embodiment thereof, such is to be considered as illustrative only, and not restrictive, the scope of the invention being defined in the subjoined claims.

35 What I claim and desire to secure by U. S. Letters Patent is:

1. An electrical signaling device comprising a vibratory resonance member including a pair of vertically disposed tines, one of which merges into a horizontal plate, a vibratory member having a head for engaging the plate and imparting vibration to the resonance member, and switch controlled electrical means and connections for effecting vibration of the vibratory member.

40 2. An electrical signaling device comprising a transparent casing, a transformer having a primary and opposed secondary coils within the casing, an elongated yieldable vibratory member extending between the secondary coils, opposed yieldable contacts intermediate the primary and secondary coils engageable with the vibratory member, electrical connections between the contacts and the respective opposite secondary coils, a push button controlled circuit connected with

45 50 55 60 the contacts, an electrical connection between the secondary coils and the vibratory member, and vibratory resonance means within the casing in proximity to the vibratory member for engagement thereby in the vibration thereof upon operation of the push button.

3. An electrical signaling device according to claim 2, together with a lamp in said casing and in circuit connection with said secondary coils.

4. An electrical signaling device according to 65 claim 2, wherein said resonance means comprises a vibratory resonance member on each side of said first vibratory member, each resonance member including a pair of free-ended tines.

5. An electrical signaling device according to 70 claim 2, wherein said casing comprises a glass cover having a vibration frequency common with said vibratory resonance means.

6. An electrical signaling device comprising a casing including a vertically disposed base, a transparent cover removably attached to the base,

a transformer within the casing and including a primary coil and spaced axially aligned secondary coils, a vertically disposed yieldable strip member extending between the secondary coils and having a head on the upper end thereof, push button controlled electric circuit connections for alternate energization of the secondary coils for imparting vibration to the strip member, and a vibratory resonance member including a pair of spaced free-ended tines disposed on each side of the strip member and engageable by said head for vibration of the resonance members.

7. The structure according to claim 6, together with stop means providing a constant amplitude of vibration of the strip member, and adjustable supporting means for said resonance members for varying the vibration of the resonance members with a consequent variation in range of tone.

8. The structure according to claim 6, together with a pair of lamps in electrical circuit with said secondary coils for providing a visible signal upon energization of the coils.

9. The structure according to claim 6, wherein said cover is formed of glass of such thickness that the cover has a vibration frequency equal to that of the resonance members.

10

15

20

25

10. An electrical signaling device according to claim 2, wherein said vibratory member is provided with a triangular shaped head, and wherein said vibratory resonance means includes flanges parallel with and engageable by opposed faces of said head, and means supporting said resonance means from the casing for adjustment of the flanges relative to said opposed faces.
